UNITED STATES PATENT OFFICE

1,992,178

LUBRICATING INSTALLATION

Joseph Bijur, New York, N. Y., assignor to Auto Research Corporation, a corporation of Delaware

Application March 26, 1929, Serial No. 349,932

22 Claims. (Cl. 184—1)

My present invention is concerned primarily with central lubricating systems, more particularly for motor vehicles, such as automobiles and while not limited thereto, it relates especially to automatic feed systems, that is, to systems that feed lubricant to the bearings during the running of the vehicle, without the need for any conscious manipulation by the user.

While the manual operation of a lubricating system, such as that specifically illustrated in the drawings of my prior Patent No. 1,632,771 of June 14, 1927, will give an inherent indication of the need for replenishment, an automatically operating feed system is subject to the difficulty that the user is not apprised of the depletion of the source of lubricant and may not even become aware of the fact that lubrication is not occurring until squeaks or more serious manifestations give belated warning that the vehicle has not been lubricated.

It is accordingly, an object of the invention to provide in a lubricating system and more particularly in an automatic feed lubricating system, means for giving timely notice to the operator of the need for a fresh supply of lubricant.

Another object is to provide apparatus or means of the above type of simple and inexpensive construction, dependable to give an indication or alarm upon depletion of lubricant, and to give no false indication, regardless of the varying conditions of vehicle operation, as long as a sufficient supply of lubricant remains.

Another object is to provide means of the above type the use or operation of which shall not involve drain upon the storage battery or other source of energy available on the vehicle, which shall involve no parts that require delicate or critical positioning on the vehicle and no separate or exposed element subject to injury.

Another object is to provide an indicator or alarm of the above type, the action of which shall not be impaired by heat, by moisture or by jamming due to vibration.

Another object is to provide an indicator or alarm of the above type, which will give the indication of depletion in an unmistakable manner, yet not so obtrusively as to be a nuisance to the operator or to passers-by.

The invention in one aspect utilizes the damping effect of lubricant in the reservoir to maintain inactive an indicator element capable of functioning by inertia in the absence of a sufficient supply of lubricant during normal vehicle operation.

Specifically, the damping effect of lubricant

maintains two relatively movable correlated elements out of contact or engagement with each other under all conditions of vehicle operation, whether over smooth or rough roads, while in the absence of a sufficient supply of lubricant, the two correlated elements are capable intermittently of engaging, in one embodiment to close an electric circuit controlling any suitable form of electric indicator, preferably a lamp, in another embodiment to produce a warning sound by their impact.

In one specific embodiment the correlated contact elements include a mass loosely retained within the reservoir and adapted to strike preferably the bottom, the wall or cover of the reservoir, thereby to produce a sound.

In one specific embodiment the mass is mounted on the end of a spring leaf anchored at one end to the bottom of the lubricant reservoir and thereby submerged in lubricant until substantial depletion of the tank.

In another specific embodiment a clapper is pendant and impacts the wall of the reservoir, and is actuated by the inertia movement of an operating mass at the outer end of an arm secured to the pendant clapper member and near the upper end thereof.

In another specific embodiment, the sound producing mass may be mounted on one leaf secured to the cover, a pendant member the movement of which is damped by lubricant in the reservoir restraining vibration of the leaf.

In the accompanying drawings, in which are shown one or more of various possible embodiments of the several features of the invention,

Fig. 1 is a diagrammatic view showing a fragment of an automatic chassis lubricating system,

Fig. 2 is a view in longitudinal cross-section taken on line 2—2 of Fig. 3 showing one embodiment of reservoir and with parts broken away to reveal operating mechanism,

Fig. 12 is a transverse sectional view on line 12—12 of Fig. 11,

10 Fig. 13 is a circuit diagram of the embodiment of Figs. 11 and 12.

Fig. 14 is a fragmentary view similar to Fig. 11 showing another embodiment, and

Fig. 15 is a top view of the indicator mechanism of Fig. 14.

15 In Fig. 1 of the drawings there is indicated diagrammatically an automatic lubricating system including a lubricant reservoir 20 illustratively mounted at the front of the dashboard and feeding a distributing system, a fragment of which 20 appears at 21. Since the specific arrangement by which automaticity is effected is not material to the invention herein claimed, I have for the sake of clearness, illustratively indicated in a purely diagrammatic manner only one of various possible arrangements for attaining this action. Referring to Fig. 2 the reservoir illustratively includes a diaphragm 22 near the upper end thereof connected by a pipe 23 for application thereto of suction from the intake manifold of the engine. 25 Under substantial variations of suction in the normal operation of the vehicle, the diaphragm 22 will flex upward and will thereupon return under the action of a spring 24. The pump plunger 25 is connected by link 26 and rod 27 to diaphragm 22 30 and is lifted for pump charge by upward flexure of the diaphragm, and caused to discharge by expansion of spring 24. Appropriate inlet and outlet valves (not shown) but the principle of which appears in Fig. 5 govern the intake by the 35 pump and the discharge to the distributing system 21.

In the embodiment of Figs. 2 and 3 the indicator is a clapper member comprising a stamped metal weight 28 horizontally disposed and preferably segmental in shape for a vane action, provided with a downturned clapper tongue 29 adapted to strike the reservoir bottom. The weight is riveted at 30 to the end of a flexible spring leaf 31 extending generally horizontally 40 across the reservoir and anchored at its opposite end by rivets 32 to an inclined bracket 33 which in turn is riveted at 34 to the reservoir bottom. Fig. 2 shows the normal position of the clapper whether the reservoir be full or empty.

45 The stiffness of the spring leaf 31 is such that the inertia of its clapper weight 28 under normal operation of the vehicle on an average road with the reservoir empty or nearly empty will produce no substantial swaying, until the vehicle strikes a rut, ridge, gutter, railway track, or other substantial depression, irregularity or obstruction in the road. When such bump is encountered the upward or downward movement of the vehicle will cause the corresponding relative inertia 50 movement of the horizontally mounted mass 28 against the resilience of the leaf 31, causing the clapper tongue 29 to strike the floor of the reservoir. The consequent sound is somewhat like that of a distant cow bell. The sound by reason 55 of its occasional occurrence is effective as a signal, where a continuous or loud staccato alarm would be a nuisance.

When the reservoir is filled with lubricant, well 60 above the level of spring 31, the vibration is ineffective to produce a sound because the move-

ment of the clapper weight with its vane 28 is damped or retarded by the lubricant in which it is submerged. As the level of lubricant in the reservoir recedes the sound will at first be but faint and as the reservoir becomes further depleted, it will become louder until when the reservoir is completely empty, it is of maximum loudness, thus giving a more and more insistent alarm in the event of continued neglect to refill.

The frequency of clapping and the intensity thereof will depend on the stiffness and length of the spring leaf mount, and the mass of the clapper. The proportions will be selected in accordance with the character of use to which the vehicle is to be put and the loudness and frequency of alarm desired. For ordinary pleasure car use, I find that satisfactory results are obtained by employing a spring leaf, as in the embodiments of Figs. 2 and 3, 4 inches in length, $\frac{1}{2}$ inch in width and made of .008 gauge steel.

20 In Fig. 4 is shown a metal bracket 35 which may be secured as by screws 36 near the top of the reservoir 20. To the inner part of this U-shaped bracket is secured by means of screws 37 the upper end of a spring metal leaf 38 to the lower end of which a clapper weight 39 is secured by means of rivets 40. The weight is a button facing the wall of the reservoir and having an associated damping vane 41 curved with its concavity facing the center of the reservoir. Riveted to the leaf 38 near the upper end thereof is the upstanding end 42 of a horizontal bar 43 preferably of thicker and less resilient metal than leaf 38. At the outer end of bar 43 a weight 44 may be secured by means of a bolt 45.

25 Normally vane 41 will damp the vibration of leaf 38 and therefore of the associated arm 43 and weight 44, although the latter be well above the level of lubricant in the reservoir. As the reservoir becomes depleted, the damping action 30 of course diminishes and finally ceases altogether. At such times the occasional bump encountered by the running vehicle will cause an upward or downward swing of mass 44 with consequent snapping of leaf 38 and impact of button 39 against the wall of the reservoir. The consequent occasional alarm stops when the reservoir is refilled.

35 In Figs. 5 and 6 is shown an embodiment in which the clapper strikes the cover rather than the reservoir wall, and in this instance the reservoir is shown as a separable element suspended from the cover, the latter carrying not only the clapper but all of the other operative mechanism. The cover 50 is welded to lugs 51 turned in from a bracket 52 by which the cover is mounted to the dashboard or other support (not shown).

40 The pump unit comprises a metal capsule having cups 53 and 54 housing the diaphragm 55 and secured by means of the suction inlet nipple 56 to the cover 50. A tube 57 is soldered to the lower cup 54 of the diaphragm capsule and mounts at its lower end the pump block 58 which may be secured thereto by a pair of cross pins 59. The pump plunger 60 extends longitudinally 45 through block 58, and is connected by means of a link 61 to rod 62 axially of tube 57 and secured at its upper end at 63 centrally of diaphragm 55. A spring retainer cup 64 rests on the ends of pin 65 transversely through the link 61 and sustains the lower end of a coil compression spring 66 50 within the tube 57 the upper end of which spring reacts against the cup 54.

55 The pump plunger draws its charge past an inlet ball check valve 67 therebelow. Only filtered 55

oil is drawn past inlet valve 67 since the supply to the latter is controlled by a filter disk 68 therebelow retained in the downwardly extending rim 69 of a cup 70 staked to the lower end of the block 58. An outlet check valve 71 is mounted in the side of the block 58, is seated by spring 72 and feeds through pipe 73 to outlet nipple 74 in the cover 50 to which nipple the distributing pipe system (not shown) is connected.

10 The oil reservoir is shown as a cylindrical vessel 75 having a flange 76 extending within the flange 50' of the cover and urged upward against the latter by means of appropriate releasable hasps 77 hinged at 78 to the cover 50.

15 Since the reservoir 75 does not mount any of the operating mechanism and is not called on to resist any of the strains due to pump operation, but serves merely as the container for the supply of lubricant, it may be of glass which affords 20 the obvious advantage of permitting inspection of the contents without dis-assembly or removal of any of the parts.

25 The construction of Figs. 5 and 6 thus far described is not per se claimed herein but is the subject matter of a copending application, 468,790, filed July 18, 1930.

30 The clapper indicator in the present embodiment comprises a resilient leaf 79 riveted at 80 to a downturned bracket 81 which in turn is riveted as at 82 to the lower side of the cover. At 35 the free end, the leaf 79 has an angle piece 83 of heavier stock with an upstanding edge normally, as shown, somewhat below the cover. The same rivets 84 which preferably connect angle piece 83 to the upper face of leaf 79, affix a damping blade 85 to the lower surface of said leaf spring. The damping blade is preferably a metal strip, extending downward within the reservoir 40 to somewhat above the bottom thereof and having an inturned foot 86 integral therewith.

45 It will be understood that as the level of lubricant in the reservoir becomes low and the damping effect of the pendant damping blade 85 greatly diminishes, the resilient metal blade will be unrestrained in its flexure resulting from the inertia of the angle piece 83 when the vehicle strikes a rut, ridge or other substantial irregularity. The edge of the weight will accordingly strike the metal cover once in a while giving the occasional alarm 50 signal, until damping medium is restored by refilling the reservoir.

55 In the embodiment of Fig. 7 the sound is produced by impact of a suspended mass. Illustratively and preferably this mass is a heavy metal ball 90 to which is soldered a carrying hook 91 affixed to the lower end of a chain 92 the upper end of which is preferably secured to a hook 93 struck out from the removable filling cap 94.

60 It will be obvious that the amplitude of vibration of the pendulum weight will be greatly restricted when the reservoir 20' has oil in it well above the level of the ball, while upon depletion or substantial depletion of the reservoir the ball will swing relatively freely under vibration. The 65 ball being mounted as shown, it would require a substantial jolt to cause it to swing sufficiently to strike the wall of the reservoir with sufficient impact to produce a readily audible sound.

70 In the present embodiment the reservoir and cover remain unmodified and require no brackets, or rivet holes therefor, the indicator device being assembled with the removable cover.

75 In the embodiment of Figs. 8, 9 and 10 the sound is produced by the impact of a ball which however is guided in a race or runway extending

transversely, preferably diametrically across the reservoir, slightly above the bottom thereof. The runway illustratively is formed from a length of sheet metal having a bottom 96, upturned longitudinal sides 97 and inturned flanges 98 which prevent the ball 99 from being thrown upward out of the runway.

80 The bottom 96 has upturned end tongues 100 which are riveted at 101 to the reservoir wall to mount the runway. Preferably the longitudinal 10 edges or corners of the runway have spaced drain apertures 102.

85 In normal operation the ball is submerged under the lubricant and will therefore not move substantially and will make no readily audible 15 sound. Whenever the lubricant drops to a level below that of the top of the runway 97 the damping effect of the lubricant upon the ball becomes less until as the level drops to the base of the runway and the contents thereof become completely 20 drained through the apertures 102, the ball will be free to roll toward one or the other end of the gutter. Preferably the gutter 96 is arranged to extend transversely of the vehicle in which relation the movements of the ball will occur less frequently than for a longitudinal arrangement so that sound will result by impact of the ball with the wall of the reservoir, in manner and at intervals resembling the action of the other embodiments previously described.

90 In the embodiment of Figs. 11 to 13 a resiliently mounted mass 105 is provided generally similar to that of the embodiment of Figs. 2 and 3, but in this instance the mass is caused when low level occurs not to produce sound by impact, but to effect closure of an electric circuit producing a signal preferably at the dashboard, for indicating low level.

95 Illustratively the spring leaf 106 is riveted to a bracket 107 on the reservoir bottom and carries 40 the metal ball 105 composed of two segments at the outer end thereof and riveted in place at 105'. Lateral vanes 108 integral with leaf 106 project laterally from the ball and serve to damp vibration. The ball constitutes one of the elements of 45 a circuit closer including a stationary spring leaf contact 109 mounted upon an insulating plate 110 secured to and extending through the bottom of the reservoir, with an associated depending binding post 111 connected by a conductor 112 with the 50 electric signal. Whenever ball 105 engages spring contact 109, binding post 111 is grounded by way of ball 105 spring leaf 106 and bracket 107, to produce a signal in the manner described below.

55 The signal is preferably a red lamp 113 mounted at the dashboard behind a disk 114 bearing the normally invisible legend "Refill chassis lubricator" or equivalent direction. The other terminal of the lamp is connected to the terminal 115 of the primary winding 116 of the ignition coil 60 which is energized from the grounded storage battery 117 when the ignition switch 118 is on.

65 As long as there is an adequate supply of lubricant in the reservoir the movement of ball 105 will be damped. When the lubricant is exhausted or nearly exhausted, an occasional substantial swing of the ball 105 will occur during vehicle operation at which times circuit closure occurs which grounds the lamp and thus closes 70 circuit from the storage battery 117.

75 As in the case of the other embodiments, the frequencies of the indications, in this case flashes of light, will increase as the condition of complete depletion of the reservoir is approached.

75 Whenever the ignition switch is opened and

the vehicle is arrested the battery circuit to the lamp is disconnected and depletion of the battery is thus avoided, even though due to mechanical derangement ball 105 should remain in engagement with contact 109 when the vehicle is at rest. As soon as the vehicle is again placed into operation (ignition switch 118 being closed) if the reservoir is still empty or nearly empty, occasional closure of the circuit through the swing of the ball 105 will occur and will give the occasional signal that the system requires replenishing. By reason of the resilience of spring contact 109, the ball in its swing will dwell for more than an instant, and the light flashes will thus be of sufficient duration to be noticed.

In the arrangement of Figs. 14 and 15 an insulating block 120 is connected by terminal screws 121 and 122 to the bottom of the reservoir. One of these screws 121 is electrically connected to a short leaf 123 carrying electric contact 124, the other of said screws 122 is electrically connected to a longer spring leaf 125 anchored at one end by screw 122 and by a clamping plate 126 on top of the insulating block. The effectiveness of the clamping plate 126 is maintained by a pressure nut 127 reacting against the said plate. The spring leaf 125 carries a weighted vane 128 riveted to the outer end thereof. Between its ends leaf 125 carries an electric contact 129 in alignment with the contact 124. The spring leaf 125 is of such length and resiliency that the electric contacts are normally separated even when the reservoir is filled with lubricant. In the present embodiment the indicator thus is a complete unitary assembly affixed in the bottom of the reservoir dispensing with the need for correlating elements separately mounted in the reservoir.

It will be understood that the embodiment of Figs. 14 and 15 is alternative to that of Figs. 11 and 12 and will preferably be used in the circuit shown in Fig. 13.

The arrangement of contacts 124 and 129 effects a dwell or wiping engagement, for effective electrical contact.

The damping effect of the lubricant on the vane 128 will prevent any vibration of amplitude sufficient to close contact. When the reservoir is empty or nearly empty, then in operation, the amplitude of vibration will occasionally, in travel over a particularly rough spot in the road, be sufficient to cause engagement of the circuit closer 124, 129 causing momentary flashing of the lamp 113 and giving the visible indication desired.

While the invention has a preferred application to automatically operated systems as above described and is not vital in a system such as that of my prior Patent No. 1,632,771, of June 14, 1927, in which the absence of lubricant in the reservoir gives an inherent indication upon manual operation, the invention is, of course, not limited to automatic systems and may be utilized to advantage in connection with manually or pedally operated or controlled systems of the type that do not give inherent indication of depletion, and also as an added safeguard to such as do give such inherent indication.

While the invention has its preferred application in automobile chassis lubricating systems, it is not limited to such use, but may be applied to other mechanisms or installations subject to irregular vibrations in the normal use or operation thereof.

I claim:—

1. In an automatic lubricating system for a machine subject to vibration in use, the combination of a lubricant container thereon, and alarm means including a vibratory part responding to vibration of the machine and having a contact part therefor in the container and maintained from giving an indication by the viscosity of lubricant submerging said parts and resilient means associated with said part and resisting movement at all times.

2. In a lubricating system for a vehicle, the combination of a reservoir, a resiliently mounted inertia member within the reservoir subject to vibration in movement of the vehicle, means to cause a signal actuated by said inertia member, the damping effect of a substantial residue of lubricant in the reservoir impeding the movement of said inertia member to prevent effective operation of said signal means.

3. In a lubricating system for a vehicle the combination of a reservoir, a clapper mass mounted within the reservoir and subject to vertical vibration in movement of the vehicle, means to cause a signal actuated by said clapper mass, the damping effect of a substantial residue of lubricant in the reservoir impeding the movement of said clapper mass to prevent effective operation of said signal means.

4. A mechanical depletion indicator for a metallic liquid container on a vibrating mechanism, said indicator including a vibratory impact member within the container and subjected to vibration of the mechanism and arranged for striking contact with said container, and cushioned from making sound upon said striking contact when submerged in liquid, said impact member including an inertia weight supported by a resilient leaf spring member rigidly connected at one end to the inertia weight and at the other end to the container.

5. In an automatic lubricating system for a vibratory mechanism, the combination of a lubricant reservoir subject to vibration with the mechanism and a clapper member in said reservoir adapted to strike a part of the wall thereof and maintained by the presence of a substantial residue of lubricant therein from sound-producing impact under vibration of the mechanism.

6. In an automatic lubricating system for a vibratory mechanism, the combination of a lubricant reservoir subject to vibration with the mechanism, a flexible member retained at one end thereof in substantially fixed position in said reservoir and having a weight affixed at the free end thereof within said reservoir, and adapted to strike a part of the wall of the latter, said weight maintained by the presence of a substantial residue of lubricant in the reservoir, from sound producing impact under vibration of the mechanism.

7. In an automatic lubricating system for a vibratory mechanism, the combination of a lubricant reservoir subject to vibration with the mechanism, a resilient carrying member affixed at one end with respect to said reservoir and a weight carried substantially at the free end of said resilient member and within said reservoir, said weight adapted to strike a part of the enclosing wall of the reservoir and maintained by the presence of a substantial residue of lubricant therein, from sound producing impact under vibration of the mechanism.

8. In a centralized lubricating system for motor vehicles, the combination of a lubricant reservoir unit, adapted to vibrate in a substantially

vertical plane in movement of the vehicle, and a clapper unit having a fixed mount with respect to the reservoir unit and a movable clapper part to produce sound by impact, said clapper unit including an inertia part to produce the impact of the clapper part under vibration, the lubricant within the reservoir cushioning the movement of said inertia part to prevent sound when the reservoir has a sufficient charge of lubricant.

9. In a lubricant reservoir for an automatic chassis lubricating system the combination of a spring leaf attached with respect to a wall of the reservoir, and extending substantially horizontally with respect thereto, an inertia member near the free end of the spring leaf for swinging under vibration of the vehicle and means under the influence of said inertia member to impact a wall of the reservoir, said means being damped against sound producing impact under the effect of lubricant in the reservoir.

10. A lubricant reservoir for an automatic central chassis lubricating system including the combination therewith of a spring leaf riveted to the floor of the reservoir, and a clapper member secured to the outer end of said spring and adapted to strike the floor of the reservoir to produce a sound under vibration in the absence of lubricant in the reservoir.

11. A reservoir for a central chassis lubricating system including a bracket affixed to the floor of the reservoir, a spring leaf affixed at one end to said bracket and extending substantially transversely across the bottom and a combined inertia device and damping vane riveted to the outer end of the spring leaf and having a downturned clapper lug adapted to strike the floor of the reservoir.

12. In a supply reservoir for a chassis lubricating system, the combination of a vibratory electric circuit closer restrained against vibration by the presence of a substantial charge of lubricant in the reservoir, electric signal means in circuit with said circuit closer and means interlocked with said engine and in series with said circuit closer to open said circuit, thereby to disable the signal while the engine is out of operation.

13. A supply reservoir for a central chassis lubricating system, having vibratory means therein damped by the presence of a substantial charge of lubricant, an electric circuit closer under control of said vibratory means, an electric signal device in circuit with said circuit closer, the ignition switch of the engine being in series with said circuit closer and said signal.

14. In a chassis lubricating system, the combination of a lubricant reservoir having a metal leaf affixed thereto near one end thereof, an inertia weight on said leaf and near the free end thereof, an electric contact mounted in said reservoir, a part on said resilient leaf adapted under vibration to contact and close circuit with said electric contact, one of said coating contact members being grounded and the other insulated with respect to said reservoir.

15. A lubricant reservoir for a central chassis lubricating system, including a loosely sustained weight therein and subject to movement under vibration of the vehicle, a circuit closer contact having an insulated support in a wall of the reservoir and adapted for connection to an electric signal device, said weight grounded to the reservoir for grounding the circuit closer when said weight establishes contact of said circuit closer.

16. In a lubricating system for a vehicle, the combination of a reservoir, a clapper mass re-

silently mounted within the reservoir and subject to vibration in movement of the vehicle, a signal contact part governed by said clapper mass, the damping effect of a substantial residue of lubricant in the reservoir impeding the movement of said clapper mass to prevent effective operation of said signal contact part.

17. In a lubricating system for a vehicle, the combination of a reservoir, a clapper mass mounted within the reservoir and subject to reciprocatory vibration in movement of the vehicle, said reciprocatory movement away from and toward the interior of said reservoir and of small amplitude when said reservoir is full and large amplitude when nearly empty, a signal causing means actuated by said clapper mass when said mass is undergoing vibration of large amplitude when said mass is at the end of its movement away from the interior of the reservoir, the damping effect of a substantial residue of lubricant in the reservoir impeding the movement of said clapper mass to prevent effective operation of said signal means.

18. In a lubricating system for a vehicle, the combination of a reservoir, a clapper mass mounted within the reservoir and subject to reciprocatory vibration in movement of the vehicle, said vibration being away from and toward the interior of said reservoir and of small amplitude when said reservoir is full and large amplitude when nearly empty, a signal causing means actuated by said clapper mass when said mass is undergoing vibration of large amplitude at the end of its movement away from the interior of the reservoir, the damping effect of a substantial residue of lubricant in the reservoir impeding the movement of said clapper mass to prevent effective operation of said signal means, said signal means including an electrical contact.

19. In a lubricating system for a vehicle, the combination of a reservoir, a guided and confined inertia member within the reservoir, subject to reciprocatory vibration toward and away from the wall of the reservoir in movement of the vehicle, the damping effect of a substantial residue of lubricant in the reservoir impeding the movement of said inertia member to prevent effective contact with the wall of the reservoir, the normal amplitude of movement of said member being sufficient to cause effective contact, whereby a warning signal is caused.

20. In a lubricating system for a vehicle, the combination of a reservoir, a clapper mass resiliently mounted within the reservoir and subject to reciprocatory vibration in the movement of the vehicle, said reciprocatory movement being away from and toward the interior of said reservoir, said movement being of relatively low power and taking place relatively slowly when said reservoir is full and being of relatively high power and taking place relatively quickly when said reservoir is nearly empty, signal causing means actuated by said clapper mass when said mass is undergoing said relatively quick movement with relatively high power and when said mass is at the end of its movement away from the interior of the reservoir, the damping effect of a substantial residue of lubricant in the reservoir impeding the movement of the clapper mass to prevent effective operation of said signal means.

21. In a lubricating system for a vehicle, the combination of a reservoir, a guided and confined inertia member within the reservoir, a signal causing means associated with said reservoir, said guided and confined inertia member being

resiliently mounted within the reservoir and subject to reciprocatory vibration toward and away from said signal causing means, the damping effect of a substantial residue of lubricant in the reservoir impeding the movement of said inertia member to prevent effective contact with the signal causing means, the undamped movement of said inertia member being sufficient to cause effective contact, whereby a warning signal is caused, said inertia member being so confined that it will not leave its normal position even though the reservoir be inverted.

22. In a lubricating system for a vehicle, an indicator for giving a signal when the lubricant supply needs replenishing, said indicator comprising a relatively fixed element and a resiliently mounted relatively movable element actuated upon movement of the vehicle to periodi-

cally contact with said fixed element when the lubricant requires replenishment, said fixed element comprising a reservoir assembly provided with cylindrical side and relatively flat bottom walls, said walls forming part of the said fixed element, and said movable element consisting in part of an inertia mass of relatively great weight and means to confine the reciprocatory movement of said weight so that it will move toward and away from said walls through a fixed path within said reservoir assembly, said inertia member being of such mass that when the lubricant supply is substantially depleted it will approach said walls with sufficient velocity to cause a warning signal and said confining means preventing loss of the inertia member even though the reservoir assembly be inverted.

JOSEPH BIJUR.
